UNITED STATES PATENT OFFICE.

FRED L. MANNY, OF BENTON HARBOR, MICHIGAN, ASSIGNOR, BY MESNE ASSIGNMENTS,
TO BAKER-VAWTTER COMPANY, OF BENTON HARBOR, MICHIGAN, A CORPORATION
OF MICHIGAN.

FOLLOWER FOR FILING-TRAYS.

1,226,790.

Specification of Letters Patent.

Patented May 22, 1917.

Application filed May 29, 1916. Serial No. 100,438.

To all whom it may concern:

Be it known that I, FRED L. MANNY, a citizen of the United States, residing at Benton Harbor, in the county of Berrien and State of Michigan, have invented certain new and useful Improvements in Followers for Filing-Trays, of which the following is a specification.

My invention relates to an adjustable back or follower adapted to be slidingly moved from front to rear of a tray or box, such as trays ordinarily used as card index containers, or for filing cabinets for the reception and classification of letters, or bills, or other documents in accordance with methods now largely followed in commercial establishments. The object of my invention is the provision of simple and effective adjusting mechanism adapted to permit the back plate to move freely in a forward direction, but arranged to automatically lock the plate against rearward movement except when a releasing member is operative to permit such movement. With this object in view I have devised the mechanism illustrated in the accompanying drawings and hereinafter described in detail, and my invention consists in the arrangement and organization of cooperating parts, the essential elements thereof being more particularly pointed out in the appended claims.

Figure 1 of the drawings is a perspective of a filing tray showing a back plate or follower in which my invention is embodied; Fig. 2 is a rear view of the follower; Fig. 3 is a horizontal section on the line 3-3 of Fig. 2, the bottom of the figure extending toward the front of the box; and Fig. 4 is a detail of one of the two brackets and slides to which the follower plate is secured but detached from the follower and tray, the view being a perspective of the left hand bracket as the same would be arranged if viewed from above and in front of the tray.

The same reference characters indicate the same parts in all the figures of the drawings.

While my invention may be applied to trays or boxes varying considerably in size and proportions, I have chosen for purposes of illustration and description a tray of well known character and proportions and forming the drawer of a suitable cabinet, such as is in common use for containing the cards of a card index catalogue, or a system of classification of some similar description.

In order to adapt such tray for my invention the sides thereof have secured to their top edges sheet metal strips 1—1 longitudinally bent as shown in the drawings—see Figs. 1 and 2,—to form longitudinal slideways each having a horizontal bottom 2, side wall 3, and top wall 4 which is recurved to constitute a depending marginal retaining flange 5. The flange 5 and top wall 4 are cut away at the front of the box (see Fig. 1) a sufficient distance to permit the insertion of the slides, hereinafter to be described, which carry the follower and parts of the adjusting mechanism mounted upon it.

The follower plate, as illustrated, may be conveniently formed of sheet metal bent to form an inclined wall 6 extending nearly to the bottom of the tray and forming the card support, a horizontal top 7, and a depending rear flange 8. Rigidly secured to the opposite sides of said follower plate adjacent its top are the slides 9 which are arranged to run in the slideways above described, these slides in the present instance being formed integral with a pair of brackets 10 which are secured to the opposite upper corners of the follower plate. The brackets, intermediate the slides 9 and downwardly inclined attaching strips 11 which are secured to the follower plate, have horizontal portions 12 which extend under the top 7 of the follower plate. At the opposite side of the follower, and interposed between its top 7 and the horizontal portion 12 of the brackets are two filler blocks 13 having their outer edges slightly inclined with respect to the direction of the slides, in such manner that the faces of the lugs spread away from each other and toward the adjacent slides from rear to front. The arrangement and proportions of the parts are such that the slides 9 may be inserted downwardly on the bottoms 2 of the tracks and slid rearwardly in the slideways opposite any portion of the retaining flanges 5, which flanges, as shown in Figs. 2 and 3, will lie adjacent the opposite ends of the top 7 and its connected flange 8 of the follower plate, and form tracks with which the rollers hereinafter mentioned cooperate. In the box which is formed at each side of the follower by the horizontal portion 12 of the bracket, the adjoining parts of the wall 6, top 7 and flange 8 of the follower plate, the flange 5 of the slideway and the inclined face of the block 13, is ar-

ranged an annular roller 14 which forms one of the gripping members of the adjusting mechanism. These rollers are normally pressed yieldingly forward by the upturned 5 ends of a spring-pressed rod 15 which is journaled in bearing clips 16 secured to the under sides of the brackets and which is equipped with a finger-piece 17 by which it may be oscillated to shift the rollers rearwardly into the wider end or part of the box 10 in which it is housed. The adjustment is such that the rollers will be wedged between the inclined face of the block 13 of the follower and the roller track formed by 15 the flange 5 of the slideway at a point near, or somewhat forwardly of the center of such face. It may be noted that when the follower and associated parts are removed from the tray the slides 9 form retainers which 20 close the outer sides of the roller housings.

From the description which has been given the operation of my device will be apparent. It is manifest that a rearward pressure against the follower plate will only 25 tighten the grip of the rollers against the flanges 5, owing to the wedging action of the inclined faces of the blocks 13, although the plate can be moved easily in a forward direction without manipulating the finger 30 piece 17, since the tendency of the ball to roll on the flange 5 does not result in wedging it against the block. When it is desired to adjust the follower plate rearwardly, the finger piece is operated, and the rollers being 35 thereby shifted into the wider part of the box in which they are housed, in which position they can offer no resistance to a relative movement of the parts.

It will be understood that the various 40 parts described as secured together and forming at opposite sides of the follower a slide and a box for housing the rollers and a bearing for the oscillating operating rod need not be separate pieces, but may be 45 formed integral, so far as convenient and desired; and that various structural modifications and changes of proportion may be made without departing from my invention. I therefore do not limit myself in the 50 following claims to the exact and specific construction above described.

I claim:

1. In combination with a tray provided 55 with a slideway and a roller track, a follower equipped with a slide member adapted to run in said way, a roller housing carried by said follower and formed with a wedging surface, and a spring-pressed roller coöperating with said track and said wedging surface.

2. In combination with a tray provided at 60 its sides with opposite slideways and opposite roller tracks, a follower equipped with a pair of slides adapted to run in said ways, a 65 pair of roller housings at the opposite sides

of said follower formed with wedging surfaces, a pair of spring-pressed rollers arranged to coöperate respectively with said tracks and wedging surfaces, and releasing means common to both rollers.

3. In combination with a tray having 70 slideways adjacent the upper edges of its sides, said slideways including retaining flanges constituting a roller track adjacent each slideway, a follower equipped with a 75 pair of slides adapted to run in said ways, a pair of roller housings adjacent said slides formed with wedging surfaces, a pair of spring-pressed rollers arranged to coöperate respectively with said tracks and wedging 80 surfaces, and releasing means common to said rollers.

4. In combination with a tray provided at 85 its sides with opposite slideways and opposite roller tracks, a follower equipped with a 90 pair of slides adapted to run in said ways, a pair of roller housings at the opposite sides of said follower formed with wedging surfaces, a pair of annular rollers arranged to coöperate with said tracks and wedging surfaces, and a reciprocating releasing member 95 having its ends formed to engage the openings in said rollers.

5. In combination with a tray provided at 100 its sides with opposite slideways and opposite roller tracks, a follower equipped with a 105 pair of slides adapted to run in said ways, a pair of roller housings at the opposite sides of said follower formed with wedging surfaces, a pair of rollers arranged to coöperate with said tracks and wedging surfaces, and a rock shaft formed with cranks at its ends connected with said rollers and arranged to shift them simultaneously.

6. In combination with a tray provided at 110 its sides with opposite slideways and opposite roller tracks, a follower equipped with a 115 pair of slides adapted to run in said ways, a pair of roller housings at the opposite sides of said follower formed with wedging surfaces, a pair of annular rollers arranged to coöperate with said tracks and wedging surfaces, and a manually operable work-shaft formed with cranks at its ends arranged to engage the openings in said rollers and shift them simultaneously.

7. In combination with a tray having 120 slideways adjacent the upper edges of its sides, a follower comprising a plate including a front wall, a horizontal top and a depending rear flange, said follower plate being equipped with bracket pieces each including a slide, a horizontal intermediate portion and an attaching strip, and adjacent portions of said front wall, top and flange 125 of the follower plate and slide and horizontal portion of the bracket piece forming walls of a roller housing, a wall having a wedging face and rigidly secured in place to form the remaining wall of the housing, and 130

roller gripping means inclosed in said housing.

8. In combination with a tray having slideways adjacent the upper edges of its sides, said slideways including retaining flanges constituting a roller track adjacent each slideway, a follower comprising a plate having a depending front wall and a top wall and equipped with a pair of slides adapted to run in said ways, and a gripping roller mounted on the rear side of said front wall and under the top wall of the follower plate and arranged to coöperate with said roller track.

15 9. In combination with a tray having slideways adjacent the upper edges of its sides, said slideways each including a retaining flange and said retaining flange being cut away at the front of the tray, a follower plate including a wall which is inclined downwardly and forwardly, said follower plate being equipped at its opposite

upper corners with a pair of forwardly projecting supporting slides which are adapted to be inserted in said slideways opposite the cut-away portions of the retaining flanges. 25

10. In combination with a tray having slideways adjacent the upper edges of its sides, said slideways including retaining flanges constituting a roller track adjacent each slideway, a follower equipped with a pair of slides adapted to run in said ways, a pair of roller housings, adjacent said slides formed with wedging surfaces, a pair of annular rollers arranged to coöperate with said tracks and wedging surfaces, and a manually operable rock shaft formed with cranks at its ends arranged to engage the openings in said rollers and shift them simultaneously. 30 35
